UNITED STATES PATENT OFFICE

1,966,108

SHOE SOLE PRESSER

Arthur F. Totz, Detroit, Mich.

Application March 4, 1932, Serial No. 596,877

7 Claims. (Cl. 12—33)

My invention relates to a new and useful improvement in a shoe sole presser, adapted for pressing a sole against a shoe for affixing the same thereto by gluing. It has been found from 5 experience that a presser member when engaging the sole and pressing the same against the shoe, while the glue is drying and particularly in that type of presser, where a heating element is used for assisting the drying operation, that it is necessary that the presser, at that part of the shoe 10 where the sole progresses into the shank, be so formed that additional pressure will be exerted upon the sole, and particularly adjacent that portion where the sole and the shank meet so 15 that a close adherence of the terminating portion of the sole with the shoe may be effected and thus a close seal accomplished.

It is an object of the present invention to provide a structure in which an arrangement may be 20 present which will accomplish this desired pressure at the desired point.

It is another object of the present invention to provide a sole presser having the portion thereof 25 adapted to engage the shank of convex contour at that side which engages the sole.

It is another object of the present invention to provide in a shoe sole presser of this class, a frame swingably mounted on a hood, and having convex prongs at opposite sides for engaging the 30 pressing element, so as to present the pressing element against the shoe at the portion of the shank adjoining the sole in a convex form.

Other objects will appear hereinafter.

The invention consists in the combination and 35 arrangement of parts hereinafter described and claimed.

The invention will be best understood by a reference to the accompanying drawing which forms a part of this specification and in which,

40 Fig. 1 is a side elevational view of a presser head showing the invention applied thereto, and illustrated in a central, vertical, sectional view.

Fig. 2 is a view taken on line 2—2 of Fig. 1.

Fig. 3 is a fragmentary bottom plan view of 45 a sole presser embodying the invention.

In the drawing I have illustrated the invention with a hood or head 7 attached to a supporting rod 8, which is slidable vertically in a standard 50 rod 9. Projecting inwardly from the head 7 are supporting bosses 8', which serve to support within the head or hood 7 a heating element 9', this heating element being spaced from the head and also from the pressing element, which is carried by the head. As shown in Fig. 1, the forward side 55 of the head or hood 7 is inclined as at 10 to

provide for the desired circulation of air. Secured to the under side of the edges of the hood or head 7 are metal straps 11 and 12, which are connected with the springs 13 to a flexible presser element formed from interlaced transversely extending straps 14, and longitudinally extending straps 15, preferably made from metal. Plates 16 and 17 are connected by the springs 18 to the end portion of the presser element. These plates 16 and 17 are secured to the under surface of the 65 prongs 19 and 20, which project outwardly from and are preferably formed integral with the yoke 21, which is swingably mounted on the head or hood 7 by means of the bolts 22. A handle 23 is carried by the yoke 21, and swingable on 70 the handle 23 is a latch member 24 having a nose or dog 25 engageable with the teeth on the segment bar 26, which is mounted on the hood or head 7. As clearly appears in Fig. 1, the under surface or pressing surface of the prongs is 75 formed arcuate as at 27, so that the presser element is given a convex formation at that portion which is adapted to engage the end portion of the shoe and the shank 28 which is positioned on the last 29 supported on the support 30. By 80 having the end portion of the presser member arranged in this shape, the desired pressure on the shank and the portion of the sole, which terminates at the shank, may be obtained and no excessive pressure on the remainder of the sole 85 will be present, and in this way a close pressing of the sole throughout its entire area becomes possible, so that an effective affixing of the sole to the shoe throughout its entire area is accomplished. By relieving, with this formation, 90 the remainder of the presser from excessive strain, the life of the pressing element is considerably increased, and a durable structure thus provided.

While I have illustrated and described the 95 preferred form of my invention, I do not wish to limit myself to the precise details of structure shown, but desire to avail myself of such variations and modifications as may come within the scope of the appended claims.

Having thus described my invention, what I claim is new and desire to secure by Letters Patent is:

1. In a sole presser of the class described, a flexible presser element; and a pair of presser 105 prongs, one at each side of said element at one end thereof and secured thereto, for pressing said element against a shoe, the pressing face of said prongs being convex.
2. In a sole presser of the class described, a 110

- flexible presser element; a yoke swingably mounted; and a prong projecting rearwardly from each side of said yoke and attached at one face to opposite edges of said presser element adjacent one end, the face of each of said prongs being convex. 3. In a sole presser of the class described, a presser head; a flexible presser element mounted on said head and free therefrom adjacent one end; a yoke swingably mounted on said head; a pair of prongs on said yoke having convex faces; and means for securing said convex faces to the free end of said flexible element at opposite sides thereof. 4. In a sole presser of the class described, a flexible presser element; and a pair of presser prongs each having a convex face, and each secured to said presser element at one end and at opposite sides thereof with the convex face in engagement with the presser element. 5. In a sole presser of the class described, a supporting head; a flexible presser mounted on said head and free therefrom adjacent one end; and a pair of spaced presser members mounted on said head and engaging opposite sides of the free end of said element and adapted for pressing against the same on a convex area. 6. In a sole presser of the class described, a supporting head; a flexible presser member mounted on said head and free therefrom adjacent one end; a pair of spaced presser members rockably mounted on said head and engaging opposite edges of the free end of said element and shaped to render said free end of said element longitudinally convex; and means for rocking said members in unison with each other. 7. In a sole presser of the class described, a supporting head; a flexible presser member mounted on said head and free therefrom adjacent one end; a pair of spaced presser members rockably mounted on said head and secured to opposite sides of the free end of said element; and means for rocking said spaced presser members relatively to said head for pressing against the free end of said flexible presser on a longitudinally convex area without disturbing the pressure on the remainder of said flexible presser.
